UNITED STATES PATENT OFFICE.

LUCIUS L. CULVER, OF ST. LOUIS, MISSOURI.

DESIGN FOR FRAME FOR CLOCK-MOVEMENTS.

Specification forming part of Design No. **11,151**, dated April 8, 1879; application filed March 12, 1879.
[Term of patent 3½ years.]

To all whom it may concern:

Be it known that I, LUCIUS L. CULVER, of St. Louis, county of St. Louis, in the State of Missouri, have originated and Designed a Frame for the Works of Clocks, of which the following is a full, clear, and exact description, reference being had to the accompanying drawing, making a part of this specification, which is a face view of the front part of the frame.

My design includes two nearly upright side portions, leaning slightly toward each other, thicker at the base than at the top, and each rounded at the foot. The two uprights are joined by three arched connections, the two lowermost being further connected by a short upright in the center line, which appears to project a little beyond the lower arch at the bottom and the middle arch at the top. This short upright is rounded at both ends. All the arches are of equal radius and about equal thickness. All arch upward.

In the drawing, A A represent the slightly-inclined upright portions, and a the rounded foot of each. B is the upper arch, connecting

the top. C and D are the lower arches. E is the short central upright, connecting C and D in the center line, and e¹ e² are the round ends, projecting, respectively, above C and below D.

It will be understood that the appearance of the fronts will be somewhat affected by the presence of the pendulum, portions of the gear, &c., in front of the frame; but such form no part of my design, and these parts, as also the clock mechanism beyond, which appears through the openings and outside of the frame, may be varied at will.

The general effect is massive, tower-like, strong. The color may be yellow brass, smoothly finished and lacquered; or the surface may be variously enameled to present an attractive appearance.

What I claim as my invention is—

The design for clock-frames, as herein set forth and described.

LUCIUS L. CULVER.
